SOUND RECORDING

Glenn L. Dimmick, Erlton, N. J., assignor to Radio Corporation of America, a corporation of Delaware

Application June 26, 1937, Serial No. 150,515.

11 Claims. (Cl. 179—100.3)

The present invention pertains to sound recording and, more particularly, to sound recording by the use of a galvanometer for the purpose of producing photophonographic sound records with a minimum of ground noise. It was proposed in Kellogg patent, No. 1,740,406, to record variable area sound records by the use of a galvanometer moving along a line parallel with the axis of movement of the sound record which 5 records with a minimum of ground noise. It was proposed in Kellogg patent, No. 1,740,406, to record variable area sound records by the use of a galvanometer moving along a line parallel with the axis of movement of the sound record which 10 galvanometer directed a triangular beam of light upon a narrow slit. It was further proposed in my application Serial No. 610,302, filed May, 9, 1932, now Patent No. 2,093,423, Sept. 21, 1937, to apply the same method to the production of 15 push-pull sound records, i. e., sound records having complementary sound waves on the several halves of the sound track. It was also proposed in my application Serial No. 137,905, filed April 20, 1937, to use a plurality of complementary triangles in the light aperture in order to record a negative sound track from which a positive sound track having ground noise reduction could be printed.

An application of Karl Schwarz, Serial No. 25 139,850, filed April 30, 1937, discloses that the aperture defining the configuration of the light beam upon the slit may advantageously be made of variable contour. In this Schwarz application, it was proposed to use a pair of leaves 30 movable about a pivot to change the configuration of a V-shaped aperture.

I have discovered that, if the movable leaf or shutter of such an aperture is pivoted at its middle point, it is possible to produce either volume expansion, volume compression or ground noise reduction without the introduction of extraneous sound. The present invention pertains to apparatus for and methods of the application of the aforesaid discovery to the production of sound records.

One object of my invention is to provide a method of, and apparatus for, producing ground noise reduction without the introduction of extraneous noises.

Another object of my invention is to provide a novel means for providing volume compression or expansion either in the recording or reproducing of sound records.

Another object of my invention is to provide 50 an improved shutter arrangement which will change the shape of the light aperture without affecting the total quantity of light transmitted thereby.

Other and incidental objects of my invention 55 will be apparent to those skilled in the art by

a reading of the following specification and an inspection of the accompanying drawing wherein

Figure 1 is a perspective view of a sound recorder including a schematic diagram of the circuit thereof.

Figure 2 is an elevation of the improved shutter mechanism as applied to the aperture plate of Fig. 1, and

Figure 3 is an elevation of the improved shutter arrangement as applied to a somewhat different form of aperture plate.

Referring to Fig. 1, the usual exciter lamp is indicated at 1, from which light is transmitted through the condenser lens 2 to the aperture plate 3, hereinafter described in greater detail. 15 From the aperture plate 3 the light is transmitted through the lens 4 to the galvanometer mirror 5, which reflects it through the lens 6 to the light slit plate 7 whereon an image of the apertures in the aperture plate 3 is formed by 20 the lenses 4 and 6. Light from these images, indicated at 8 and 9, is transmitted through the slit 10 in the plate 7, and is focused by the objective 11 upon the photographically sensitive film 12 for recording the sound record. 25

When the mirror 5 is vibrated in accordance with the sound impulses to be recorded, the aperture images 8 and 9 are correspondingly vibrated across the slit 10, causing an increase or decrease in the respective areas intercepted, and thereby producing a push-pull sound record, as 30 described in my aforesaid Patent 2,093,423.

The sound impulses to be recorded are applied to the translating device 13 which may be any source of electric impulses, such as a microphone, a phonograph pick-up, a telegraphone, the output of a radio receiver, etc. The output from this sound to audio current translating device is fed to the amplifier 14 where it is amplified and passed to the galvanometer winding 40 15', which serves to vibrate the mirror 5 in accordance with the audio frequency impulses. A portion of the output from the amplifier 14 is transmitted to the bias amplifier 15, where this portion of the output is amplified, rectified and 45 filtered to produce a pulsating uni-directional current corresponding to the envelope of the sound waves or the volume of the sound in the manner described, for example, in McDowell Patent No. 1,855,197. The output from this amplifier is passed through a coil 16, which serves to actuate a pair of shutters 27 and 28, as described and claimed in the copending application of J. O. Baker, Serial No. 82,375, filed May 28, 1936 for the purpose of limiting the exposure 50 55

area to the amount actually used in recording the particular sound impulses as described and claimed in the aforesaid McDowell patent. A portion of the output from the amplifier 16 is also passed through the coil 17 which may be connected in series with the coil 16, as indicated, or connected to the bias amplifier 15 in any other desired manner and which serves to actuate the movable shutters 18 and 19 pivoted to the aperture plate 3.

It should be noted that these shutters are pivoted at their middle points, as indicated at 20 and 21, Fig. 2, and that, therefore, when they are rotated about their pivots, one end tends to close the aperture, while the other end tends to open it, and the total quantity of light passing through the respective triangular apertures 22 and 23 is thereby caused to remain constant. It will be apparent that if the pull rod 24 is caused to move downwardly by the magnet 17, the slope of the shutters 18 and 19, and therefore the slope of the hypotenuses of the triangular images 8 and 9 will be increased, while at the same time the shutters 27 and 28 will be opened. When the bias amplifier is so connected that this is done in response to an increase in the amplitude of the sound, the shutters 27 and 28 are opened sufficiently to allow for the increased amplitude, while at the same time the increased slope of the shutters will cause a decrease in the proportionate amplitude of the record. Otherwise stated, the shutters 18 and 19 will compress the volume of the recorded sound impulses. Likewise, if the amplitude of the sound is decreased, the shutters 27 and 28 will move inwardly, the rod 24 will move outwardly, the shutters 18 and 19 will move into a more nearly horizontal position, and increased sensitivity of the apparatus will result as the amplitude decreases, thereby compressing the volume of the recorded sound.

If it is desired to expand the volume of the recorded sound, all that is necessary is to reverse the connections to the bias amplifier from the amplifier 14 and to move the solenoid 16 to the opposite side of the arm which it actuates; or the bias amplifier and the solenoid 16 may be left as shown and the solenoid 17 may be connected to actuate the opposite ends of the shutters 18 and 19 in the same direction as illustrated; or the solenoid 17 may be left in its illustrated position and the rod 24 extended so that the core of the solenoid lies below, instead of above, it. If either of these changes is made, then an increase in input from the translating device 13 will cause the shutters 18 and 19 to move to a position more nearly parallel to the slit 10, while a decrease in amplitude will cause them to move to a position more nearly transverse to the slit 10 and volume expansion will result. The action of the ground noise reduction shutters 27 and 28 will, of course, remain as before.

The apparatus as above described is intended for what is known as class "A" push-pull recording with ground noise reduction. In that type of recording, as will be apparent from an inspection of the apparatus just described, two similar sound records are produced, one on each half of the sound track area, these records being 180° out of phase and the portion of the sound track area not used in the sound record being obscured by the shutters.

If it is desired to use the improved apparatus of my invention to produce a bilateral sound track wherein the wave images on the two halves

of the sound track are in phase so that the sound track can be reproduced on an ordinary single photocell reproducer as distinguished from the push-pull reproducer necessary for the sound track above described, the form of aperture 5 shown in Fig. 3 may be used. This aperture and the use thereof are, in general, the same as described in the aforesaid Baker application, Serial No. 32,375, distinguishing therefrom, however, in that shutters 18 and 19 are provided to change 10 the configuration of the sloping edges of the aperture. In this arrangement, the rod 24 is connected by appropriate lengths to either the inner ends or the outer ends of the shutters 18 and 19, instead of being connected to either the 15 left hand ends or the right hand ends of the shutters in the species of the invention shown in Fig. 1. It will be apparent that since in this sound track both halves are to be identical, the action of the shutters will be correspondingly 20 the same as in Fig. 1, increasing the slope of the aperture on both sides simultaneously on increasing amplitude and decreasing it on decreasing amplitude, if volume compression is to be secured, or the reverse if volume expansion is to 25 be produced.

It will be apparent to those skilled in the art that my invention is not limited to the specific forms thereof shown in the drawing, but that the improved centrally pivoted shutters, or one 30 of them, may be used to advantage in connection with practically any type of aperture used in variable area recording to change the angular relation between one or more sides of the aperture and the other side or sides.

Having now described my invention, I claim:

1. Apparatus of the class described, including means for projecting an image of a light aperture upon a slit, means for moving said image in accordance with the impulses to be recorded, and means for changing the shape of said image in accordance with the amplitude of said impulses while maintaining a substantially constant area of said image.

2. Apparatus of the class described, comprising means for projecting a triangular beam of light upon a narrow slit, and means for changing the angle of at least one side of said triangle in accordance with the amplitude of the sounds to be recorded without changing the area of said triangle.

3. Apparatus of the class described, comprising a pair of shutters movable about their middle points to define the shape of a light beam, means for moving said shutters in accordance with the envelope of the sounds to be recorded, and means for vibrating said light beam in accordance with the sounds to be recorded.

4. Apparatus of the class described, including means for projecting an image of a light aperture upon a slit, means for moving said image in accordance with sounds to be recorded, and means for varying the angular relation between the sides of said image in accordance with the amplitude of the sounds to be recorded without changing the area of said image.

5. Apparatus of the class described, comprising means for projecting a triangular beam of light upon a narrow slit, and means for changing the angular relation between the sides of said image in accordance with the amplitude of the sounds to be recorded without changing the area of said image.

6. Apparatus of the class described, comprising a pair of shutters movable about their middle

points to define the shape of a light beam, means for changing the angular relation between the edges of said shutters in accordance with the envelope of the sounds to be recorded, and means for vibrating said light beam in accordance with the sounds to be recorded.

7. Apparatus of the class described, comprising means for projecting a pair of triangular beams of light upon a narrow slit, and means for changing the angle of at least one side of each of said triangles in accordance with the amplitude of the sounds to be recorded without changing the area of said triangles.

8. Apparatus of the class described, comprising a pair of shutters movable about their middle points to define the shape of a pair of light beams, means for moving said shutters in accordance with the envelope of the sounds to be recorded, and means for vibrating said pair of light beams in accordance with the sounds to be recorded.

9. Apparatus of the class described, including means for projecting images of a pair of light apertures of complementary configuration upon a slit, means for moving said images in accord-

ance with sounds to be recorded, and means for varying the angular relation between the sides of said images in accordance with the the amplitude of the sounds to be recorded without changing the area of said images.

10. Apparatus of the class described, comprising means for projecting a pair of oppositely oriented triangular beams of light upon a narrow slit, and means for changing the angular relation obetween the sides of said images in accordance with the amplitude of the sounds to be recorded without changing the area of said images.

11. Apparatus of the class described, comprising an aperture plate having a pair of oppositely directed triangular apertures, a pair of shutters movable about their middle points in relation to said plate to vary the shape of a pair of light beams, and means for changing the angular relation between the edges of said shutters and said apertures in accordance with the amplitude of the sounds to be recorded.
